UNITED STATES PATENT OFFICE.

LINCOLN V. JOHNSON AND FREDERICK J. FISHER, OF SAN FRANCISCO, CALIFORNIA.

CONTAINER-STOPPER.

1,260,389.

Specification of Letters Patent. Patented Mar. 26, 1918.

Application filed April 2, 1917. Serial No. 159,126.

To all whom it may concern:

Be it known that we, LINCOLN V. JOHNSON and FREDERICK J. FISHER, citizens of the United States, and residents of the city and county of San Francisco, State of California, have made a new and useful invention—
to wit, Improvements in Container-Stoppers; and we hereby declare the following to be a full, clear, concise, and exact description of the same.

The objects of this invention are to make a device of this character that is simple in construction, durable in nature and beneficial to the public.

Another object is to provide a container that is held sealed by the inclosed contents, thereby insuring a positive preventing of leakage.

A further object is to make a stopper that will hold the inclosed contents intact when placed in any position.

In the specification and the annexed drawing, the invention is illustrated in the form considered by us to be the best, but it is to be understood that the invention is not limited to such form, as it may be embodied in other forms, and it is also to be understood that in and by the claims following the description it is desired to cover the invention in whatever form it may be embodied.

In the drawings:

Figure 1 shows a container partially in section with the device applied therein.

Fig. 2 is a view illustrating the means of opening the stopper to allow flow.

Fig. 3 is a sectional view of a stopper.

Fig. 4 is a view of the stationary member.

Fig. 5 shows the manner of inserting the device into a container.

Fig. 6 is the common form of opener used.

As illustrated in the accompanying sheet of drawing, the container, designated by the numeral 1, is shown having the neck or throat 2 thereon with the stopper, generally

designated as 3, secured therein. It is to be understood that the invention is not confined to the shape of the container shown, as by enlarging or reducing the size of the device it can be applied to any vessel having an ex-

tended outlet.

The stopper 4 and the projections thereon are unitary in construction, and it has been

found that to make a serviceable device, capable of being subjected to long, hard usage, that rubber with the sulfur blossom removed is a very dependable material, but other materials can be used.

Rubber as here defined consists of either caoutchouc, gutta percha or india rubber, or by any other of the titles that this elastic, resilient substance comes under.

The stopper 3 consists of the flat resilient member 4, with the spud or lug 5 formed on the lower face thereof approximately the same diameter as the inner outlet 7 of the container throat 2, where it joins the shoulder 8 of the container 1. On the top face 9 opposite the side 6 of the member 4 is a resilient projection 10 preferably formed of the same material as the stopper 4 extending at right angles thereto and of less diameter than the plug 5. The free end of the projection 10 terminates and is secured in the piece 14.

The bridge member 14 is made of a material that is not susceptible to the deleterious effects of acids or alkalis. The member as shown in Fig. 4 consists of a flat wedge-shaped piece of material 14 having the hole 16 bored therein and the section between the hole 16 and the wide top 17 of the wedge, split, as shown at 18. The function of this slot 18 is, that when the resilient member 10 is secured in the hole 16 of the piece 14 and the device 3 forced down into the throat of a container, as in Fig. 5, the outward draft of the throat 2 will gradually impede progression of the member 14 and that by using greater force behind the member 14 at this point, the two sides of the wedge will partially close and bind the member 14 in position in the neck. As the member 15 assumes a permanent position in the neck 3, the hole 16 will have become smaller, and in turn exercised a tighter grip on the container member 10.

The member 4 after the piece 5 has become fixed, assumes a position as indicated in Fig. 5. The sides of the piece 4 overlap the lug 5 forcing the stopper 3 into a container, will bend upward around the smaller projection 10. When the member 4 enters the interior of the bottle it readily expands to a flat normal position and when downward

pressure is released, is pulled upward by the elastic elongated projection 10 to be stopped by the shoulders of the outlet 7.

The member 4 cannot be drawn up through the container throat 2 because of the lug 5 that prevents any downward bend, to the extent of allowing the member 4 to be made small enough to allow it to go back up through the throat. The thickness of the piece 4 added to each side of the diameter of the lug 5 is of greater width than the internal diameter of the throat 2 and it is this fact that prevents the removal of the stopper.

15 This stopper is commercially valuable as a means for sealing a container without any danger of the seal being broken and the contents allowed to escape.

For pouring contents from the container, 20 any means for depressing the piece 4 to break the seal can be used. By way of illustration, Fig. 6 shows the means 25 we employ, but a match or a wire could be used in an emergency. This depressor 25 can be 25 left in the container without danger of falling out when the container is inverted.

Having thus described our invention what we claim and desire to secure by Letters Patent is:

30 1. In combination with the throat of a container, of a rigid means fixed therein; a stopper engaging the inner outlet of said throat, and resilient means integral with said stopper connecting said stopper and said rigid means for holding said stopper in engagement.

2. In combination with the throat of a container having a rigid means secured therein, of a stopper covering the inner 40 outlet of said throat; elastic means integral with said stopper connected to said rigid means; and an elastic projection on the side of the stopper opposite the elastic means.

3. In combination with the throat of a 45 container having a rigid means secured therein, of a stopper covering the inner outlet of said throat; elastic means integral with said stopper connected to said rigid

means; an elastic projection on the side of the stopper opposite the means; and means 50 for depressing the stopper.

4. In combination with the throat of a container having a rigid means secured therein of a stopper covering the inner outlet of said throat; resilient means connecting said rigid means and stopper integral with said stopper.

5. In combination with the throat of a container having a rigid means secured therein of a stopper covering the inner outlet of said throat; resilient means integral with said stopper connected to said rigid means; and means for depressing the stopper.

6. In combination with the throat of a 65 container having a rigid means secured therein of a rubber stopper covering the inner outlet of said throat; and rubber means connecting said rigid means and stopper, integral with said stopper.

7. In combination with a container having a throat; a transverse bridge fixed in said throat; and a stopper closing said throat and having an integral resilient extension engaging said bridge.

8. In combination with the throat of a container having a rigid means secured therein of a rubber stopper covering the inner outlet of said throat; rubber means integral with said rubber stopper connected to said rigid means and means for depressing the stopper.

9. In combination with a container having a throat a transverse bridge fixed in said throat; and a rubber stopper closing said 85 throat and having an integral rubber extension engaging said bridge.

In testimony whereof, we have hereunto set our hands at San Francisco, California, this 27th day of March, 1917.

LINCOLN V. JOHNSON.
FREDERICK J. FISHER.

In presence of—

BALDWIN VALE,
A. J. HENRY.
